UNITED STATES PATENT OFFICE.

JAMES LESLIE MENNELL, OF LONDON, ENGLAND, ASSIGNOR TO CHAS. BUTTERS & CO. LIMITED, OF LONDON, ENGLAND.

APPARATUS FOR INDICATING THE DENSITY OF LIQUIDS AND AUTOMATICALLY GRADING THE SAME ACCORDING TO THEIR DENSITY.

Application filed November 30, 1920. Serial No. 427,402.

To all whom it may concern:

Be it known that I, JAMES LESLIE MENNELL, a subject of the King of Great Britain, residing in London, England, have invented 5 certain new and useful improvements in apparatus for indicating the density of liquids and automatically grading the same according to their density, of which the following is a specification.

10 The apparatus forming the subject-matter of this invention is designed to give a continuous indication of the density of a liquid as it flows through a tank and to deliver such liquid as it leaves the tank to one 15 of a number of launders or other receptacles, according to its grade or density.

In this apparatus the rise and fall of a 20 sinker submerged in the liquid in the tanks, caused by change of density of the liquid 25 produces a rotary movement of a spindle which carries a pointer and an electric contact spring or brush. The pointer moves across a scale of densities and the brush moves across a series of contacts which 30 control the operation of an electric motor by means of which a pivoted launder, into which the liquor from the tank flows, is shifted into one or other of a number of definite positions depending upon which of the series of 35 contacts is for the time being operative, according to the density of the liquor in the tank. The sinker is suspended in the tank from one end of a balanced pivoted beam, from the other end of which depends a cord 40 or its equivalent which is lapped around a suitably shaped and weighted drum or cam fast on the axle of the pointer and electric switch.

The apparatus will be more particularly 45 described with reference to the accompanying drawings, wherein Fig. 1 is an end elevation, partly in section, showing the hydrometer part of the apparatus more particularly; Fig. 2 is a side elevation of the apparatus; Fig. 3 a plan view, from which the launder is omitted; Fig. 4 an elevation, on an enlarged scale, of the indicator and switch part of the apparatus; Fig. 5 a central vertical section of the same; and Fig. 6 a detail showing the shape of the cam on the indicator spindle.

The tank through which the liquid flows for the purpose of density determination and classification, is divided into two compart-

ments *a* and *b* by a partition *c* which reaches 55 from the top of the tank nearly to the bottom of the latter. The liquid to be dealt with is delivered into compartment *a* and passes under the partition *c* into compartment *b*. Immersed in the liquor within the latter 60 compartment is a sinker *d* of definite volume and preferably of double cone form, as shown in Fig. 1, which is suspended by a rod *e* from one end of a pivoted beam or balance *f* fitted with the usual knife edge fulcrums. 65 Depending from the other end of the beam is a wire or cord *g* adjustably clamped to a knife edge bearing and having at its lower end a ribbon of steel or equivalent flexible inextensible material lapped around the edge 70 of a horizontally pivoted cam disc *h*. Fixed to the disc is a radial arm *i* upon which is adjustably mounted a bob *i'* which serves to counter-balance the sinker and keep the wire *g* in tension. The spindle *h'* of the cam 75 disc is connected through a multiplying gear train *j* with a pointer *k* which traverses a graduated scale indicated at *k'* (Fig. 2). By suitably cutting the cam *h* (as shown in Fig. 6) an equal division scale over a considerable range of density can be obtained. 80

To prevent further movement of the beam *f* when the liquid in the tank is of greater or less density respectively than the highest and lowest value for which the apparatus is designed, a pair of stops *e'*, *e''* is provided on the rod carrying the sinker, these stops being preferably adjustable relative to the sinker and to each other and being adapted to engage a fixed stop or abutment *e'''* projecting 90 from the frame of the apparatus.

The tank may be fitted with a steam coil *l* or equivalent heating device to prevent crystallization of the liquid due to fall of temperature and to maintain a constant or 95 substantially constant temperature when the apparatus is in use.

Below the outflow *b'* of the tank is a launder *m* carried by the pivoted frame of a segmental rack *n*. A pinion *n'* gearing with 100 this rack is driven by means of an electric motor *o* which is controlled by electric circuits established by the momentary contact of a contact spring or brush *k'* carried by the pointer *k* with one or other of a series 105 of contacts *p* swept over by the brush *k'* as the pointer *k* traverses the density scale. The contacts *p* preferably consist of metallic

rollers carried by brackets p' adjustably clamped to a ring q of insulating material concentric with the pointer spindle so that the contacts are angularly adjustable with respect to each other. By suitable adjustment of the contacts, the grades or densities into which the liquor is classified may be varied.

The automatic operation of the electric motor and the arrangement of circuits and apparatus by means of which it is effected is no part of the present invention, being substantially identical with the arrangement of circuits and apparatus used in the well known electric elevator or lift, and no claim is herein made to such apparatus per se, nor has it been considered necessary to describe it beyond stating that the electric control of the motor is such that when the brush k' touches a given contact p the motor is started up and through the connecting gear swings the pivoted launder m into one of a number of definite positions according to the particular contact stud p which engaged the brush k' . These definite positions correspond with the grades or densities into which the liquor has to be classified, and in each definite position of the pivoted launder the liquor is delivered by it to a definite receptacle or launder according to grade. The switch arrangements of the control circuits of the electric motor are such that the motor stops automatically when the launder reaches the position corresponding with the particular contact p , the momentary connection of which with the brush k' initiated the movement of the motor and launder, and the motor does not re-start to move the launder to another position until the brush k' makes contact with another of the contacts p . Such movements involve the use of limit and reversing switches actuated by a tappet carried by the moving body which in the case of the automatic electric lift is the cage or lift carriage and in the apparatus under consideration is the pivoted launder or segmented rack.

Having thus described the nature of the

said invention and the best means I know of carrying the same into practical effect, I claim:

1. An apparatus for classifying liquid according to its density, comprising a hydrometer balance, an electric switch actuated thereby to traverse a series of electric contacts, an electric motor controlled by said switch and operating to swing a pivoted launder into definite positions, substantially as described.

2. In conjunction with the apparatus of claim 1, an indicator which shows the density of the liquor in the hydrometer balance tank.

3. An apparatus according to claim 1, wherein the electric contacts are arranged to be relatively adjustable so as to vary the grades or densities of classification, substantially as described.

4. An apparatus for classifying liquid according to its density, comprising a hydrometer balance, an electric switch actuated thereby, an electric motor controlled by said switch and means actuated by the said motor and operating to deliver the liquid into different receptacles according to its density.

5. An apparatus for classifying liquid according to its density, comprising a hydrometer balance, a pivoted launder and electric means controlled by the said balance and operating to swing the said launder into different positions according to the density of the liquid.

6. An apparatus for classifying liquid according to its density comprising a liquid containing tank, a hydrometer balance having its sinker mounted for submergence in the liquid in the tank, means for discharging liquid from the tank into any one of a plurality of receptacles, and electric means controlled by said balance and operating to connect the said discharging means with the several receptacles according to the density of the liquid.

In testimony whereof I have signed my name to this specification.

JAMES LESLIE MENNELL.
